UNITED STATES PATENT OFFICE.

EARLE S. JUDD AND RALPH RUSSO, OF SOUTHBURY, CONNECTICUT.

PAPER-HANGER'S BOARD.

Application filed December 8, 1925. Serial No. 74,150.

Our invention relates to improvements in paper hangers' boards and the object of our improvement is simplicity and economy in construction and convenience and efficiency in use. 5

In the accompanying drawing:—

Figure 1 is a plan view of our improved paper hanger's board in the folded or closed position, being in part broken away to show 10 one end of the slot for housing the zinc straight edge, the joint for the arm extension, and certain other details.

Figure 2 is a similar view in the position for use, the arm extensions for extra widths 15 of paper being shown, and an extra board section being indicated by broken lines.

Figure 3 is an end elevation in the fully opened position, with the guide section extending the width at the top, and the arms in 20 pendant position for use as supporting legs.

Figure 4 is a sectional view on an enlarged scale on the line 4—4 of Fig. 2 through the adjustable hinge.

Figure 5 is a sectional view on the line 25 5—5 of Fig. 2, through one of the indexes.

Figure 6 is a diagrammatic plan view under conditions of use with a roll of paper, part thereof being in the cutting position, with markings, numbered, to indicate figures 30 on the paper that require matching with incidental waste or surplusage of paper, and the setting of the indexes to correspond.

Our improved paper hanger's board comprises a main section 10 at the middle; a 35 front section 11 that serves to extend the width of the board, and a guide section 12 at the rear that cooperates with the other sections in different ways according to the position, as will be described, said sections being connected along opposed edges by means of 40 sets of hinges 13.

The board when set up for use is supported by horses as usual and of collapsible and portable form and when paper is used that 45 is extra wide an extra section 14 of board may be used along the front.

The guide section 12 may be opened out so as to serve to provide additional width to the board as a whole for use in applying the 50 paste to the paper and in such position the arms 15 and 16 that are hinged thereto are brought to a pendant position so as to serve as additional supporting legs.

In the cutting operation the arm 15, adjacent one end and shown at the right in Fig. 55

2, serves as a cutter, the paper being torn or cut along the outer edge 17 thereof, and is connected to the guide section 12 by the cutter-arm hinge 15^a, so that it can be swung back and forth relatively to the cutting position. 60

At the opposite or left end the arm 16 is connected to the guide section 12 by means of the slide hinge 18 that is slidably mounted on the guide section 12 through the medium 65 of a metal plate 19 for longitudinal movement. Said left arm 16 serves as a weight or block for holding down the free end 20 of the paper. The part 21 of the paper to be operated upon extends from the arm 16 along the intervening space and under the arm 15 and the body 22 of the roll rests upon the tail end portion 23 of the board at the right. 70

Markers or indexes 24 are used in conjunction with the decorations or figures on the paper for locating the length of the paper to be cut and these are mounted for longitudinal sliding movement on the strip 19 in substantially the same manner as the slide 80 hinge 18. 75

With plain paper to be operated upon only one marker 24 would be used and preferably, in order to reduce waste of paper, the one adjacent the arm 16 and this would be adjusted to a position close to said arm 16. 85

In the case of operating upon paper having ornamental figures, requiring matching and consequent waste, the two markers 24 would be used and these would be set so that 90 the space 25 between the markers would correspond to the extra waste due to such particular paper.

Thus in Fig. 6 the exposed face is shown as marked off by a set of cross-lines comprising dash-and-dot lines 26 that alternate with broken lines 27 that indicate a difference in character and the spaces 25^a between adjacent lines determine the width of the space 25 between the markers or indexes 24. 95

Alternately the left and the right marker 24 would be used in locating the paper on the board and all of the cutting would be done along the edge 17 of the arm 15. 100

The board, as described, provides a means 105 of effecting a system of cutting.

The arms 15 and 16 comprise each a main part 28 that is made of proper length for co-operation with the main part or section 10 and the front section 11 for working upon 110

paper of ordinary widths and for use with the extra loose section 14 they are provided each with an end portion or extension 29 that provides the needed extra length. The joint 5 between the main part 28 and the extension part 29 may be of any suitable form. As shown, the extension part 29 has a pair of spaced longitudinally directed fingers 31 that project from the end face and enter within 10 suitable sockets 32 in the opposed end face of the main part 28.

Latches 33 at the ends serve to hold the board locked in the closed position.

In such closed position the free end face 34 of the guide section 12 is opposed to the free end face 35 of the front section 11 and serves as a closure for a slot 36 that enters inwardly into the adjacent end portion of the front section 11 and that extends along the 20 length thereof, being closed at the ends by plugs 37.

The slot 36 serves as a housing for a straight-edge 38, usually of zinc, that is used for trimming the paper longitudinally. 25 A notch 39 may be provided in the free edge or end face 35 for providing access to the straight-edge 38.

In the closed position the arms 15 and 16 are disconnected from the guide section 12 30 by breaking the hinges 15^a and 18 by pulling out the pintles 40; each arm retains a hinge member; the two arms are connected in alignment by means of one of the pintles 40, and they are supported against the bottom face 41 of the front section 11 by means of spring clips 42.

As shown, the hinge member 43 on the right arm 15 has a pair of spaced hinge knuckles 44 and for cooperating therewith the hinge 40 member 45 on the left arm 16 has a single middle hinge knuckle 46.

The outer hinge member 47 of the slide hinge 18 that cooperates with the hinge member 45 on the left arm 16 is the part that 45 slides along the sheet metal plate or strip 19. For cooperating as a hinge member with the single middle hinge knuckle 46 of the left arm 16 said outer hinge member 47 has a pair of laterally spaced hinge knuckles 48.

50 In order to permit of such sliding of the outer hinge member 47 the same is made in the form of a spring clip of a single piece of sheet metal that is bent to provide a return bend. Said return bend serves to inter-connect a top portion 50 and a bottom portion 51 that are opposed one to the other and spaced for gripping the portion of the sheet metal strip or plate 19 that is positioned therebetween.

60 The knuckles 48 are located at the free edge of the top portion 50 and at the free edge of the bottom portion 51 there is a downwardly directed lip or finger 52.

65 The lip 52 cooperates with a longitudinal groove 53 in the opposed face 54 of the mate-

rial of the guide section 12 and serves to position the slide hinge 18 laterally.

The indexes 24 are supported from the strip 19 in the same manner as the hinge 18, the clamping details being similar, and in 70 the structure the exposed body portion 55 corresponds to the top portion 50.

The edge 17 of the right arm 15 is simply a right-angled corner that serves as a straight-edge along which the paper may be torn or cut. In the use of the term cut or cutting, the generic significance of the term is implied as having reference to any manner of severing the length or strip of paper desired from the roll. Actual cutting may be employed in some cases, whereas in others, as with an experienced operator, simple tearing may be relied upon.

As described and as particularly shown in Fig. 4, the supporting hinge part 47 of the slide hinge 18 is operatively supported for sliding along the metal strip 19 by integral means that operate as a spring clamp, involving upper and lower clamping arms that are connected by a return bend of sheet metal. The downwardly directed lip 52 on the lower of said arms by engagement in the groove 53 serves to prevent sidewise movement and separation from the supporting strip and to confine movement to a sliding movement 95 along said strip.

Also, as described, the indices or markers 24 are similarly operatively confined, as shown in Fig. 5.

Considering the detail of the hinge knuckles, the supporting hinge part 47 of the slide hinge 18 comprises a pair of knuckles 48 symmetrically arranged and separated by a space for receiving the single knuckle 46 of the left arm 16. The knuckle feature for the hinge 15^a for the right arm 15 is similar to that for the arm 16, but the position thereof and relation to the connected parts is reversed, in that the two spaced knuckles 44 are provided on the hinge member 43 on the arm 15 and the single knuckle for cooperating therewith, like the knuckle 46 on the arm 16, is provided on the supporting member that is attached to the guide section 12.

The provision of the arrangement of the hinge knuckles described ensures proper connection for the arms 15 and 16 with a correct connection of the hinges by the removable pintles and, in particular, that the arm 15 that is used for severing the paper will be 120 properly connected for use.

We claim as our invention:—

1. A paper hanger's board comprising a main section, a guide section of appreciably less width than said main section, hinged by one of its edges to one of the edges of said main section, having a guide-edge for paper at the other free edge, and provided with an arm for overlying said paper that is connected to said other free edge of said guide 125

section, and the parts being constructed and arranged so that said guide section can be opened out for serving as an extension of said main section.

5. 2. In a paper hanger's board as described in claim 1, a second arm hingedly and slidably connected to said guide section for being superimposed upon paper that is being operated upon under conditions of use, and said 10 first mentioned arm having an edge for use in severing paper from the roll.

3. A paper hanger's board comprising a permanent unitary board structure that is made up of a plurality of sections arranged 15 edge to edge and an arm arranged for being positioned across said board structure and terminating substantially at the free edge of said board structure, and an extension for said arm being provided for being positioned 20 across an extra width of board for use with paper that is wider than said permanent board structure.

4. In a paper hanger's board, an elongated board structure, a pair of arms located respectively adjacent each of the ends thereof and hinged for being swung back and forth relatively to the face of said board structure, one of said arms being operative as a weight device for holding down the ends of the paper 30 delivered from the roll, and the other of said arms having an edge for severing the paper from the roll body, and said board structure being extended beyond said other arm for supporting the roll of paper from which the 35 paper is delivered for severing.

5. In a paper hanger's board, a board structure having a main section and a front and a rear section hinged to the opposite edges of said main section so as to fold over upon 40 one face of said main section, said front section and rear section when so folded having the opposed edges closely adjacent, and one of said opposed edges having a slot that extends inwardly for housing a straight-edge 45 or the like, whereby the other of said opposed edges serves as a closure for said slot.

6. In a paper hanger's board, a board, a pair of arms for being swung across said board, hinges individually connecting said 50 arms and board and comprising each a leaf for the arm that is connected to a leaf of the board by a removable pintle, and the leaf on one arm mating with the leaf on the other arm for permitting of connecting the two 55 arms together by means of a pintle.

7. In a paper hanger's board, a board structure and an arm having a straight-edge at one end thereof, and a pair of adjustable indices operatively mounted at the other end 60 of said board for alternative use in cooperation with said edge in operating upon a roll of wall paper of figured character for alternatively severing different lengths of said paper.

65 8. A paper hanger's board comprising in

combination, an elongated board structure, a guide section of relatively narrow width, opposed to the edge of said board structure and hinged thereto so as to be adapted to be opened outwardly into substantially the same 70 plane as said board structure and also to be folded over against one face thereof, and having a free edge for use as a guide edge for paper, a pair of arms hinged to said free edge, one of said arms having a paper-severing edge, the other of said arms being mounted for sliding along said board structure, and a set of indices also mounted for sliding and located adjacent said free edge.

9. A paper hanger's board comprising a main board for use in operating upon the paper for unrolling from the roll and severing into sections, arms for use in cooperation with said board in such operating upon the paper, a guide section located along one edge of said board and extended for substantially the entire length thereof, said guide section having an edge for guiding the paper, and said guide section serving as the means for operatively supporting said arms.

10. In combination in a paper hanger's board, an elongated board for receiving paper to be severed, a guide edge extending along one edge portion of said board and for substantially the entire length thereof, devices at one end of said board for use in severing said paper from the roll, and the other end of said board being provided with a slide support that is arranged so as to be in parallelism with said guide edge.

11. In a combination as described in claim 10, an arm for overlying said paper located at said other end of the board, a hinge for said arm comprising one leaf that is connected to one end of said arm, and the other leaf of said hinge being mounted for sliding on said slide support.

12. In a paper hanger's board, a board proper having a straight-edge along one edge portion, a pair of markers located adjacent one end of said board and mounted for independent adjustment in parallelism with said edge, and paper severing means at the other end of said board, whereby in using the board for severing operative lengths of figured paper from the roll, the markers serve to cooperate one with the other to indicate the difference in overall length of the alternate operative lengths.

13. In a paper hanger's board, a board proper, a pair of arms for being swung across the face of said board, hinges having removable pintles individually connecting said arms with said board and comprising a hinge member at the end of each of said arms, and the said hinge members matching one with the other for permitting of connecting said arms end to end and in alignment by the use of one of said pintles.

14. In a paper hanger's board, a board

proper having a straight-edge along one edge portion, a slideway adjacent one end of said board and located in parallelism with said edge, and devices operatively connected to 5 said slideway comprising an index and a hinge member, an arm for being swung across the face of said board being connected to said hinge member.

15. In a paper hanger's board, a board proper and an arm for being swung transversely thereover, a metal strip extended along a portion of the length of said board, and means for slidably connecting said arm to said strip in the form of a spring clamping 10 device having clamping arms for gripping said strip.

16. In a paper hanger's board as described in claim 15, said board being provided with a groove in parallelism with said strip, and 20 one of said arms having a lip that is engaged in said groove.

17. In a paper hanger's board, a board

proper and a metal strip extended along a portion of the length thereof, and an index mounted for adjustment in position along 25 said portion having means for operative connection with said strip.

18. In a paper hanger's board, a board proper, a pair of spaced hinge knuckles adjacent one end of said board and a single 30 knuckle adjacent the other end thereof, a pair of arms for use as weight devices and one thereof being provided with a severing edge, and said arms being provided individually with knuckles for mating respectively with said knuckles on the board.

19. In a paper hanger's board, a board proper, paper severing devices adjacent one end thereof, and a finger-like pointing 40 marker slidably mounted along a portion of the length at the other end of said board.
